TEXTILE MACHINERY

Frank Corbyn Hale and William Howarth, Spondon, near Derby, England, assignors to Celanese Corporation of America, a corporation of Delaware

Application August 4, 1933, Serial No. 683,620
In Great Britain August 18, 1932

4 Claims. (Cl. 139—13)

This invention relates to textile machinery, and particularly to circular looms, the object of the invention being to produce a circular loom capable of high output and a high degree of control over the type and quality of the fabric produced.

In circular looms, weaving proceeds as a continuous or substantially continuous operation, a plurality of shuttles laying weft progressively round the circle constituted by the warps and formed into sheds accommodating each shuttle, so that for each cycle of rotation as many wefts can be laid as there are shuttles in the loom. By its freedom from the intermittent operation by which ordinary weaving is carried out, and by its continuous and progressive laying of weft in the shed, the circular loom offers a rapid and economical method of weaving. However, a great difficulty, militating against high output and even against the general adoption of circular looms, is that the shuttles have to remain enclosed in the warp shed, and have therefore to be supported in position within the shed by means operating through the warps. Both from mechanical considerations and because of the necessity for protecting the warps against injury by the shuttle-supporting means, this necessary disposition of the shuttles in the warps has seriously retarded the progress of circular weaving.

One method, however, of supporting the shuttles without damage to the warps comprises the use of vaned wheels which in rotating pass through a warp sheet and enter recesses in the shuttles where they engage rollers providing abutments to prevent the shuttles and the warps moving simultaneously. On the other side, the shuttle may be supported by a roller engaging a circular race through one warp sheet. Conveniently, such shuttle-supporting wheels operate to hold the shuttles stationary, thereby avoiding the difficulty which might arise with the action of centrifugal force were the laying of weft to depend upon rotation of the shuttles. Of course such shuttle holding means may also operate to rotate the shuttles at a speed range within which undue centrifugal force does not arise, and may thus be used in a loom having both shuttles and warps rotating in opposite directions to give an output corresponding to the relative rates of rotation of the shuttles and warps.

It has been found in practice that the necessity for driving the vaned wheels at a suitable speed to enable the vanes to pass through the warps as the warps slide over the faces of the

shuttles results in a rather cumbersome mechanical gearing which requires considerable space for its support and operation. In this way the number of shuttles which can be accommodated round the periphery of a loom of any particular diameter has been limited by the necessity for accommodating the driving gear of the shuttle-holding means, with the result that a less number of shuttles has had to be employed than might be considered possible from a consideration of the space available for the shuttles themselves.

As has been pointed out above, the output of the loom depends directly upon the number of shuttles round the periphery of the loom, and because of the difficulty mentioned above it has not been possible to achieve very high outputs on account of the relatively few shuttles which could be properly held in position in the warps.

Furthermore, the limitations imposed by the necessity for employing shuttle-holding means have entirely prevented the use of other than quite a small number of shuttles in circular looms, so that in looms of convenient dimensions as regards space occupied and facility of attention, about ten shuttles have been found to be the maximum which can be accommodated. Thus while a diameter of three or four feet gives a loom which forms a very practical weaving unit, only relatively low outputs are obtainable with this diameter. The invention has for one of its principal objects the modification of circular looms to enable much larger numbers of shuttles, say twenty or twenty-four, to be utilized without interfering with the compactness and convenience of the loom as a weaving unit.

According to the present invention, a circular loom is provided with a number of shuttles, a shaft for each shuttle, vane wheels on said shaft adapted to penetrate the warps and hold the shuttles in position in the warp sheds, and a plurality of means for driving said shafts, each of said means driving a plurality of shafts. Thus, for example, a series of inter-connected shuttle-holding means may be employed which are driven at say four points round the circle. In this way as many shuttles may be supported as can conveniently be arranged to follow each other closely round the loom, subject to the ability of the shedding mechanism to change the shed properly between consecutive shuttles, as will be referred to later.

In this manner, without increasing the complexity of the shuttle-holding means or adding to the weight of the gearing involved (a point of considerable importance), the invention enables

- a circular loom to employ as many as twenty or twenty-four shuttles and still to run at the same speed as or at even higher speeds than looms with a much less number of shuttles. Quite apart, 5 however, from the output of the loom being increased, an important advantage arises from the use of a larger number of shuttles in that the adaptability of the loom for patterning purposes is enormously increased. This results from the 10 larger number of factors into which the greater number of shuttles can be divided, a twenty-four shuttle loom being capable of a repeat at intervals of say 2, 3, 4, 6 or 8 shuttles, in accordance with the fabric desired. Thus plain twill or 15 8-shaft satin may be woven on the loom by suitable adjustment of the shedding mechanism. A twenty shuttle loom is particularly suitable for the production of 5-shaft satin, as well as plain weaves, such as 1:1 and 2:2 and twills.
- 20 A convenient form of shuttle-holding mechanism according to the invention comprises a series of shafts carrying the shuttle-engaging vane wheels connected to each other so as to be driven at the same speed, this series of shafts being 25 driven by a single set of gearing. Conveniently, the shafts, each of which lies parallel to its corresponding shuttle, are connected together by a universal joint which can be of a compact nature, or, if desired, by bevel gearing, suitable guards 30 being provided for protection where the universal joint or bevel gear is exposed. In this way each shaft merely requires to be provided with suitable bearings which can easily be accommodated round the loom circle, while the set of shafts has 35 its common gear occupying very little room. Several such sets together hold all the shuttles in position, there being, however, relatively few driving points required for the sets.
- The bearings for the shafts are conveniently 40 formed in pairs carried by a single support adjacent to the connected ends of the shafts. For example, a bracket may be provided which forks at its upper end to form two bearings with a space between to accommodate the universal joint or 45 bevel gear connecting the pair of shafts. At the driving point for the series of shafts this bracket conveniently forms a bearing for the driving shaft geared at its upper end to one of the shuttle-holding shafts, or to two such adjacent shafts, 50 and provided with a gear at its lower end engaging part of the loom rotating at a suitable speed.
- As stated above, two or more series of interconnected shafts may be provided in the loom, 55 each having its own drive. Thus, for example, in a loom accommodating twenty shuttles, the driving may be effected at four points round the loom circle, so that five shuttles are provided with a common actuating means which can be 60 located at a point on the loom which does not interfere with the accessibility of the mechanism or of the shuttles when it is desired to replenish the weft supply. The shuttle-holding shafts may, however, be all connected together to form 65 a chain running round the loom, the drive being distributed among a plurality of driving points, so that the shafts and their supporting bearings and inter-connecting gear are not subjected to severe torsion and may be kept down to small 70 dimensions.
- In order to avoid damage arising by reason of jamming of the warps on breakage of either warp or weft threads, it is most desirable that means should be provided to bring relative motion 75 between shuttles and warps to an end in such event. Convenient means for this purpose are described in Jabouley's U. S. Patent No. 1,822,292. By reducing the amount and weight of gear for holding the shuttles, the invention 5 enables the shuttles and their holding gear to be rapidly brought to the speed of the warps even when the loom is running at high speed, and notwithstanding the large number of shuttles required to be set in motion. This is particularly important in looms employing twenty or 10 twenty-four shuttles which in achieving the output of a large number of ordinary looms may run at 15, 20, 25 or even more revolutions per minute and lay up to 500 or more picks per minute each 3 or 4 yards in length. The gearing 15 and shuttle-holding means are conveniently carried on a normally stationary but rotatable member which is freed so as to rotate with the warps when jamming occurs, the jamming being detected by suitable feeler members, conveniently 20 carried on the shuttles and operating to release the member. When stationary, the member permits the driving of the shuttle-holding gears through a gear rotating with the warps, but when freed allows this driving action to cease, the 25 shuttles then rotating with the warps and the vanned wheels not being required to rotate.
- In order to take full advantage of the large 30 number of shuttles which can be accommodated by the use of the gearing described above, each shuttle should follow as closely as possible the preceding shuttle and shedding is therefore effected at the earliest possible moment to enable 35 this to be effected. Since the shuttles themselves keep the two sheets of warps apart after the warps have been divided to permit the entry of 40 a shuttle, and may even be used to push the warps apart to their fullest extent after they have been separated only to a small degree by the shedding mechanism, it is possible to commence the shedding operation before the warps have left any 45 particular shuttle. In this way the warps can commence to shed before they have reached the rear of the shuttle, and though they are still kept to the original shed by the shuttle itself, they 50 spring rapidly into the new shed on reaching the rear of the shuttle and form immediately a new and opposite shed, either of full width or of sufficient width to enable the succeeding shuttle to enter and push its way between the two sheets. 55 In this way the gap between shuttle and shuttle can be made very small, and the number of shuttles in relation to the periphery of the loom increased to the maximum.
- Conveniently, the shuttle body and associated 55 parts, including the weft spool, are made of light material, such as aluminium. Further, the shuttle body itself is recessed so as to form what is practically a skeleton framework for the spool, and having recesses for engagement by the shuttle-holding wheels, and bearings for the supporting 60 roller.
- By way of example the invention will now be described in greater detail with reference to the accompanying drawing, in which:
- Figure 1 is a plan view of the shuttles and driving means therefor according to the present invention, showing also the shedding means.
- Figures 2, 3 and 4 are front elevations of shuttles showing the manner in which shedding is effected.
- Figure 5 is a view of the gearing for the shuttle driving means, and
- Figures 6 and 7 are side elevation and front elevation respectively of a shuttle of light con-

struction suitable for the purposes of the invention.

Referring to Figure 1, a part plan view of a loom having twenty shuttles is illustrated, twelve shuttles 10 being shown in the figure. The warp threads 11, 12 form sheds in which the shuttles run. The shuttles are maintained in position by means of vane wheels 14 carried upon shafts 15 rotating in bearings 16. The bearings 16 are carried on an annular plate 30 which is normally stationary. The vane wheels 14 pass through the warps 11, 12 and hold the shuttle in position while the warps, warp beams, and fabric rotate in the direction shown by the arrow. All the shafts 15 round the loom are connected together by means of universal joints 116, the obtuse angle between adjacent shafts 15 rendering this form of connection very suitable for the purpose. At every fifth universal joint 116 a bevel gear 18 is secured to one of the shafts and is driven by means of an intermeshing bevel 19, so that, round the whole circle of the loom, there are four driving points for the twenty shuttles. The shafts 15 are connected together to form an endless chain round the loom, so that the drive from each pair of bevels 18, 19 is evenly distributed in both directions. On account of the fact that several shafts 15 are driven from each driving point the shafts should be of light weight.

At the three shuttles 10x at the top right-hand side of Figure 1, the scheme of warp shedding is illustrated. The warp threads 11 and 12 pass through a reed shown at 20 in Figures 2, 3 and 4, each dent of the reed 20 having an eye 21. Alternate warp threads 11 pass through the eyes 21, while the other warp threads 12 pass between the dents of the reed. In this manner the warp threads 11 are constrained always to pass through the points 21 while the warp threads 12 can slip between the dents in the reed from one side of the point 21 to the other. Shedding is effected by means of shedding wheels 22, 23, which are disposed alternately inside and outside the warp circle and act upon the warps at a point above the reed 20.

The shedding means 22, 23 overlap the nose of one shuttle and the tail of the preceding shuttle, and engage with the warp threads as the warp threads approach the tail of each shuttle deflecting them inwardly or outwardly according to whether the wheel is outside or inside the circle of warp threads. The path of the threads 11 below the reed 20 is not affected by the shedding wheels 23, since these threads are forced to pass through the points 21. The warp threads 12 however, are pushed by the shedding wheels 22, 23 and are caused to cross past the points 21 before the shuttle has left the shed. The normal passage of the shuttle through the warp shed is illustrated in Figure 3, while the deflection of the warp threads before the shuttle has left the shed is illustrated in Figure 3. It will be noted that the shuttle 10 maintains the shed open in spite of the deflection of the threads over the top of the shuttle. As soon as the shuttle 10 leaves the shed, the warp threads spring to a new position illustrated in Figure 4, the threads 12 passing to the right hand side of the threads 11 instead of on the left hand side as shown in Figure 2. The shed shown in Figure 4 between the threads 11 and 12 is only a narrow one, but it is sufficient for the nose 24 of the succeeding shuttle to enter into the gap and to push the warps apart to form a sufficiently wide shed. The movements of the warp threads are shown in Figures 2-4 and also at the shuttles 10x in Fig-

ure 1 at which the warp threads are shown as if severed just beneath the line of the reed 20 in Figures 2-4. It will be noted that the threads 11 in Figure 1 always spring from the fabric circle shown at 25, on whichever side of the shuttle they pass, being constrained to do so by the points 21 in the dents of the reed 20. The warp threads 12 however, are deflected to one side or to the other of this line to form the narrow shed necessary for the shuttle to enter. Since the direct path of the threads 11 is constant, i. e. from the points 21 to the line of the fabric 25 it follows that alternate sheds will be on opposite sides of this line, and the shuttles 10 in Figure 1 are illustrated as being alternately slightly outside and slightly inside the line of the fabric, so that they may enter sheds formed on opposite sides of this line. The manner in which the warps are caused to spring from one shed position to the other immediately after they have passed a shuttle enables the shuttles to follow very closely after one another, so that their number can be relatively high in relation to the size of the loom.

Figure 5 illustrates the bracket for the driving gear of the shuttle holding apparatus. The foot 27 of the bracket 28 is secured by means of bolts 29 to an annular plate 30 which runs round the loom. Each bracket 28 carries two of the bearings 16, the bearings having removable caps 32 for the shafts 15. The shafts 15 are connected together by means of a universal joint 116. One shaft 15 carries the bevel gear 18 which engages with the bevel gear 19 carried on a shaft 36. The shaft 36 is held in a bearing 37 on the bracket 28 and passes through bores 38 in the base 27 and plate 30, being driven by means of a gear 40 engaging with a circular rack 41 passing completely round the loom and rotating with the warp threads. In Figures 6 and 7 a light form of shuttle is shown which is especially suitable for the purpose of the present invention. A bobbin 43 is carried upon a plate 44 which is secured to plates 45, 46 suitably shaped to separate and hold apart the warp threads. The base of the shuttle comprises a vertical plate 47 tapered at 48.

The shuttle is maintained in position by means of the vane wheels 14 rotating on a shaft 15, the wheels being vanned so as to pass through the warp threads 11 or 12. The wheels 14 engage at the top with channels 50 secured by means of webs 51 to the plate 47. At the bottom, the vane wheels engage with rollers 52 carried in bearings 53 secured to the plate 47.

It will be noted that there are two pairs of vane wheels 14, a roller 53 being provided between each pair. In order to support the shuttle on the other side, a roller 55 carried in bearings 56 on the plate 47 is provided, the roller engaging through the warp threads 12 with a conical face 57 lying inside the circle of warps. The whole construction of the shuttle is designed for lightness, for which reason the plate 47 is cut away as illustrated at 58 to reduce its weight as far as possible. At the front of the shuttle is carried a member 60 acting as a nose to the shuttle and first entering the narrow warp shed. The warp shed is subsequently parted by means of wings 61 secured to the plate of the member 60. The thread 62 drawn from the bobbin 43 passes down a channel 63 on one side of the plate 47 and through a guide eye 64 from which it is laid into the fabric.

On account of the lightness of the shuttles, the stopping of the loom in the event of warp jamming or weft failure is facilitated, despite the greater number of shuttles. Thus, a stop motion

of the type described in Jabouley's U. S. Patent No. 1,822,292 may be employed, in which the normally stationary shuttles 10, shafts 15 and ring 30 are caused to rotate with the annular gear 41 and with the warp threads. The lightness of the shuttles, and of the driving shafts 15, and the elimination of a large proportion of the driving mechanism for such shafts gives a light stationary unit which can be rapidly brought to 10 rotate with the warp threads, even when the speed of the loom, that is the rate of rotation of the warps, is high. Cessation of weaving, and subsequent complete cessation of the rotation of the loom are then brought about at an early 15 stage after a fault has occurred.

What we claim and desire to secure by Letters Patent is:—

1. A circular loom comprising a plurality of shuttles, a shaft in association with each shuttle, 20 means for connecting said shafts in a chain round the loom, vane wheels on said shafts adapted to penetrate the warps and to hold the shuttles in position in the warp sheds, a plurality of means for driving said shafts, each adapted to drive a 25 plurality of shafts, and a common driving member in direct engagement with each of said shaft-driving means.

2. A circular loom comprising a plurality of shuttles, a plurality of shafts in association with 30 said shuttles, universal joints for connecting said shafts to form a chain round the loom, vane wheels on said shafts adapted to penetrate the warps and to hold the shuttles in position in the warp sheds, a plurality of means for driving said

shafts, each adapted to drive a plurality of shafts and a common driving member in direct engagement with each of said shaft-driving means.

3. A circular loom comprising a plurality of shuttles, a shaft in association with each shuttle, 5 means for connecting said shafts in a chain round the loom, vane wheels on said shafts adapted to penetrate the warps and to hold the shuttles in position in the warp sheds, a plurality of means for driving said shafts, each adapted to drive a 10 plurality of shafts, a common driving member in direct engagement with each of said shaft-driving means, and shedding means adapted to act successively upon the warp threads before they reach the tail of a shuttle, so as to cause 15 them to spring into position immediately on passing said shuttle to form a new shed for the reception of the succeeding shuttle.

4. A circular loom comprising a plurality of shuttles of light construction, a light shaft in 20 association with each shuttle, means for connecting said shafts in a chain round the loom, vane wheels on said shafts adapted to penetrate the warps and to hold the shuttles in position in the warp sheds, a plurality of means for driv- 25 ing said shafts, each adapted to drive a plurality of shafts, said parts forming a unit of small inertia readily capable of being rotated and brought to rest when desired, and a common driving member in direct engagement with each 30 of said shaft-driving means.

FRANK CORBYN HALE.
